(57) **CLAIM**

The ornamental design for a valve assembly, as shown and described.

DESCRIPTION

In a preferred embodiment, the nature of this product is as a valve assembly for directing water to a spout.

FIG. 1 is a left, top, front perspective view of a valve assembly embodying my new design;

FIG. 2 is a front elevational view thereof, the rear elevational view being identical to the front elevational view shown; FIG. 3 is a left side elevational view thereof, the right side elevational view being identical to the left side shown; and, FIG. 4 is a top plan view thereof.

The broken line representation of mounting structure in FIGS. 1 and 4 is for the purpose of illustration only, and forms no part of the claimed design.
